CLAIM

The ornamental design for a water resistant gasket for conduits and the like, substantially as shown and described.

DESCRIPTION

FIG. 1 is a top plan view of a water resistant gasket for conduits and the like showing our new design;

FIG. 2 is a front elevational view thereof;

FIG. 3 is a cross sectional view taken along line 3—3 of FIG. 1 thereof.

Fig. 1.

Fig. 2.

Fig. 3.
